Primary Examiner — Ryan Harvey(74) *Attorney, Agent, or Firm* — Mitchell Law PLLC; Matthew W. Mitchell(57) **CLAIM**

The ornamental design for a resistance exercise band, as shown and described.

DESCRIPTION

FIG. 1 is a front, top isometric view of the resistance exercise band of the present invention;

FIG. 2 is a second isometric view thereof;

FIG. 3 is a front view thereof;

FIG. 4 is a rear view thereof;

FIG. 5 is a top plan view thereof;

FIG. 6 is a bottom plan view thereof;

FIG. 7 is a left-side view thereof; and,

FIG. 8 is a right-side view thereof.

In the drawings, the evenly-spaced broken lines within the handle portion depict stitching which forms part of the claim; the dash-dot-dash lines represent portions of the resistance exercise band that form no part thereof.
